(57) CLAIM

The ornamental design for a bottom portion of a golf club head for a putter, as shown and described.

DESCRIPTION

FIG. 1 is a perspective view of a bottom portion of a golf club head for a putter showing my new design;

FIG. 2 is a second perspective view thereof; and,

FIG. 3 is a bottom view thereof.

The broken line showing of the remainder of the golf club head for a putter and the unshown top and front of the putter form no part of the claimed design.
